WINDOW

George R. Gall, Cleveland, Ohio

Application July 19, 1945, Serial No. 606,007

9 Claims. (Cl. 20—12)

1

This invention relates to windows and more particularly to improvements in window frames and sash and in the coaction therebetween.

It is among the objects of my invention to provide a window in which the sash may when desired have great freedom of movement relative to each other and to the window frame but the window will also be weather tight precluding substantially all movement of air, moisture or otherwise through or around the window, its frame and/or between the sash, i. e., through or around the window as a whole. Another object of my invention is to provide a window which when one or more of the parts thereof are constructed of materials which tend to expand and/or contract through changes in the seasons, temperature, humidity and the like, will be capable of retaining its desired characteristics of being freely operable as well as being weatherproof. A further object is to provide a window in which the sash may be easily positioned, wholly or partly opened or closed, and may be positively secured in any desired position against movement, willful or otherwise. A further object is to provide a window the sash of which may be bodily removed from the frame whereby to facilitate the washing of the exterior faces of the sash from the interior side of the window. A further object of my invention is to provide a window in which the sash may be easily removed and/or replaced without injury to the sash or frame and by the ordinary and normal manipulation of the working parts of the window. Another object is to provide a window the manufacture, installation and use of which will be economical and which is adaptable to practice in a variety of materials or combination of materials as may be chosen either for purposes of economy or for artistic or architectural effects. A further object is to provide a window frame of such rugged and durable design and construction as to substantially eliminate the need for employment of separate lintels thereabove.

A more specific object of my invention is to provide a window frame one side of which is movable transversely of its length whereby to grip and/or release the sides of the sash as may be desired to carry out some or all of the above objects. Another object is to provide a window frame having a movable part engageable with the sides of the sash and having a yieldable sealing member through which to permit movement of the parts and maintain a weather-tight closure throughout the desired range of movement thereof. Another object

2

of my invention is to provide a window having an adjustably movable part of the frame coacting with the sash in such a manner that the sash may have around the peripheral edges thereof yielding rubber-like sealing members which may be compressed on movement of the frame member in one direction and in which the frame member has sufficient movement to effectively release the compressible sealing members.

Other objects and advantages will appear from the following description of a preferred form of my invention reference being had to the accompanying drawings in which Figure 1 is an elevation of my window in situ in a wall opening; Figure 2 is a horizontal section taken along the line 2—2 of Figure 1; Figure 3 is a vertical section taken along the line 3—3 of Figure 2; Figure 4 is a vertical section taken along the line 4—4 of Figure 1; Figure 5 is a fragmentary transverse section taken in the plane of the line 5—5 of Figures 2 and 4 at and above the level of the window sill; and Figures 6 and 7 are fragmentary sections similar to Figures 2 and 4 respectively showing provisions for window screens.

To illustrate a preferred embodiment of my invention I have shown in Figure 1 the window W comprising an upper sash 1, a lower sash 2 and a frame 3 set in a wall 4. It will be noted that the window has a conventional hasp 5 and has an operating lever 6 which may lie substantially flush with the wall surface, see also Figure 2. The handle 6 actuates the mechanism which permits the release of the sash for relative movement and conversely brings about the tight engagement of the sash to form a weatherproof and leakproof joint between the sash and the frame. For the purpose of example and not for any purpose of limitation I have chosen to illustrate my invention using more or less conventional wooden sash 1 and 2 mounted for movement in and coaction with a metallic frame 3. Preferably the frame members are formed of extruded light metal shapes as will more fully appear. I have chosen these materials for the purpose of illustration and to show the adaptability of my invention to the use of various materials and various combinations of materials.

Turning now particularly to Figure 4 the frame 3 of my window may comprise a head 10 having an upward reenforcing flange 11 integral therewith as well as downward reenforcing flanges 12 and 13 along with an inwardly positioned decorative and reenforcing flange 14,

3

the latter serving as a plaster ground or guide for the interior trim of the wall 4. As mentioned above the head 10 may preferably be formed of an extruded shape of such material as aluminum or may be rolled steel or other metal as economy and other considerations may dictate. Preferably the upward flange 11 is located inwardly of the exterior decorative wall surface, such as brick, and outwardly of the back-up tile, lath and plaster. The flanges 12 and 13 are preferably spaced to encompass the sash, sealing means and parts of the side frame members presently to be described. The bottom of the frame comprises the sill 15 preferably with a main sloping part 16 against which the bottom of the sash 2 bears, and a conventionally raised inward shelf portion 17 lying at a higher level than the outward sloping portion 16 as shown. Preferably the shelf 17 has a lip 17a facing the sash and extending between the reveal flanges 25 and 42 of the side frame members and has a downwardly extending return strip or flange 18 corresponding to the decorative strip 14 above.

The head 10 and sill 15 respectively are joined and spaced by side frame members 20 and 40 of cross sectional form which I prefer to be substantially as shown in Figure 2. One of the side frame members 20, leftwardly as viewed in Figures 1 and 2 is preferably of a unitary extruded shape fixedly related to the head and sill. The side member 40 however has movable parts and mechanisms presently to be described by virtue of which the sash are gripped or released as may be desired. Both side frame members 20 and 40 in addition to the functions about to be described, may also serve as structural columns resting on the sill and supporting the head of the frame. Preferably the side members are welded or otherwise fixedly secured to the head and sill on full bearing areas corresponding to their full cross-sectional shape as shown in Figure 2 whereby to give rigidity and strength to the whole frame structure. The head and sill preferably overlie the side members as at 10a and 15a, Figures 1 and 2.

The side frame member 20 as shown in Figure 2 preferably takes a middle box-like form 21 which with the central partition 22 conveniently forms separate wells for the sash weights 23 and 24 which may thus have free movement. Appropriate sash weight ropes or cables, see 82a, Figure 4, may pass over pulleys, not shown, in the tops of the wells and connect the weight to the respective sash. A vertical flange 25 extending, as do the other parts of the member 20, the full height of the frame lies inwardly at about the mid-portion of the central box structure 21 to set off the inner reveal of the window, and terminates in a decorative trimming flange 26 corresponding with the trimming flanges 14 and 18 of the head and sill respectively. The portion of the member 20 lying toward the outside of the window includes the stiffening flange 27 shown to be lying behind the decorative brick facing and may also comprise an outwardly extending angled flange 28 preferably terminating in a beaded terminus 29. A flange 30 lying parallel to the plane of the sash and outwardly thereof and terminating in bead 31 forms with the angled portion of the flange 28 a decorative and strengthening channel forming the outward reveal of one side of the frame, and as will hereinafter appear lies complementary to the similar structure associated with the other side member 40. The inward face of the flange 30 is prefer-

4

ably bevelled as at 32 whereby to present an inclined plane to the outward corner of the sash 1 whereby to induce the sash 1 to move inwardly of the window when the sash moves leftwardly or is moved leftwardly of the frame member 20 as viewed in Figure 2. The frame member 20 also has a longitudinal extending centrally disposed guiding rib 33 and a short flange 34 with an inclined surface complementary to the inclined surface 32 and serving the same function for the sash 2 that the surface 32 serves for the sash 1. As shown in Figure 2 the flange 30 with the guiding rib 33 forms a longitudinally extending channel 35 for the sash 1, and the rib 33 with the flange 34 forms a similar channel 36 for the sash 2. It will be observed that the rib 33 and flange 34 limit the depth of the channels 35 and 36 whereby the sash may be removed therefrom in a direction inwardly of the window whenever the sash are moved rightwardly no more than the height of the rib 33 or the flange 34.

The side frame member 40, see also Figures 2 and 3, comprises a main channel portion 41 opening toward the sash and extending the full height of the frame member. The member 40 terminates on the inward side of the window in a flange 42 complementary to the flange 25 above described and the flange 42 in turn terminates in a decorative trimming flange 43 corresponding to the trimming flanges 14, 18 and 26. The member 40 terminates on the outside side of the window in an outwardly extending angled flange 44 corresponding to the angled flange 28 and symmetrically disposed with relation thereto; the angled flange 44 terminating in a beaded terminus 45 having an exterior appearance corresponding to the bead 29, but the bead 45 contains a longitudinally extending groove 46 which receives and positively grips the outward longitudinal edge 47 of the sealing diaphragm 48. I prefer that the channel 46 be extruded in the first instance with its opening wide enough to freely receive the edge 47 and, upon receipt thereof in the course of assembly of the parts, that the channel 46 be closed tightly upon the edge 47 by forcible and permanent deformation of the material of the inner wall of the groove 46.

As shown in Figure 2 the side frame member 40 does not of itself receive directly or have direct contact with the sash 1 and 2, but rather the sash are received in and guided by a separate member 50 preferably of box-like cross-section which is movable rightwardly and leftwardly, as viewed in Figure 2, in telescoping relation within the channel 41, having a fairly close and free sliding fit therewith. The member 50 extends the full height of the frame member 40 and has a squared top in a close but free sliding fit or contact with the under surface of the head 10 and has its bottom surface area inclined to the inclination of the sloping part 16 of the sill 15 upon which it stands in smooth slidable engagement.

As shown in Figure 2, the member 50 is similar in its form to the box portion 21 of the fixed frame member 20, and has sash receiving and guiding channels 51 and 52 which preferably correspond in form and shape to the channels 35 and 36 respectively of the oppositely disposed frame member 20. The inward flange 53 with its inclined face corresponds to the flange 34; and rib 54 corresponding to the rib 33; the flange 55 corresponding to the flange 30 with an inclined surface 56 corresponding to the surface 32 and a beaded terminus 57 corresponding to

the bead 31 and symmetrically disposed oppositely thereof. The beaded terminus 57 has an inner groove 58 in which is securely gripped and received the whole length of the inner edge 47a of the diaphragm seal 48 and is secured therewith in the same way that the outer edge 47 is secured within the channel 46, that is, in a mechanically secure and substantially air tight relation.

The diaphragm member 48 is preferably formed of thin flexible metallic or other fluid impervious flexible and resilient stock of light gage whereby to facilitate the rightward and leftward movement of the box member 50, as viewed in Figure 2, whilst sealing off the elements, air and weather from entrance to the main channel 41 of the member 40 and/or between the sliding surfaces of the box 50 and the channel 41. I have found for example that sheet stainless steel of about 30 gage or less will serve the purposes of this diaphragm seal and is capable of substantially endless flexing within the requirements of life time operation of my window. Such a diaphragm will yield readily within the space provided for it, and will not be adversely effected by exposure to the elements throughout a desirably long life.

It will be observed that the sealing member 48 preferably takes the form of a deep U-shaped channel within and behind the angled flanged 44 whereby to be substantially inconspicuous either from the interior or exterior of the window and presents substantially no different appearance to the eye when the window is in use than does the empty complementary channel lying behind the angled flange 28 of the member 20.

As viewed in Figure 4 it will be seen that the diaphragm member 48 is cut squarely at the top but is cut at the bottom whereby to conform to the inclination of the sill 15 at least when the diaphragm is in the position which it assumes when the box member 50 is advanced to its leftward-most position, as viewed in Figure 2, that is to say, when the edge 47a of the diaphragm has its most leftward movement, the bottom edges of the side legs of the U of the diaphragm may be substantially square and level while the curving portion of the U of the diaphragm preferably conforms to a helix whereby to accommodate the slope of the sill 15. Since the leg of the diaphragm terminating in the edge 47a is to have movement with the box member 50, and the opposite leg of the diaphragm is to have no bodily movement rightwardly and leftwardly (but may have some movement incident to the flexing of the diaphragm) the lower edge of the curved part of the diaphragm will in its helical form tend to rise away from the sill in part when the box element 50 is moved rightwardly. To accommodate the tolerances which are desirable in production of these members, having in mind the geometrical relation above discussed, I prefer to provide a rubber-like sealing member 60, see Figures 2, 4 and 5, which may be of substantially U-shaped form as viewed in Figure 2, and is preferably of angled section as shown in Figure 5, having an upstanding leg 61 secured to the lower edge of the diaphragm 48 and having a somewhat horizontally disposed wiping lip 62 lying on and sliding over the sill 15 in wiping and sealing contact, being urged downwardly by the resiliency of the member 60. By the use of the rubber-like seal 60 the lower edge of the diaphragm need not conform precisely to the desired geometrical requirements and may merely be spaced closely enough to

the sill 15 to permit the wiping edge 62 of the rubber-like seal 60 to have continuous contact with the sill whereby to exclude all movement of air and weather from between the lower edge of the diaphragm and the sill 15. The rubber-like sealing member 60 may be secured to the lower edge of the diaphragm 48 either by cement, vulcanization or otherwise as may be found most practicable. A similar sealing member 70, see Fig. 4, may be attached to the upper edge of the diaphragm and have wiping and sealing contact with the lower adjacent surface of the head 10 whereby to seal the movable joint between the diaphragm and the head.

Referring to Figure 2 the member 50 preferably comprises two sash weight receiving wells 81 and 82 separated by a partition 80 carrying pulleys, not shown, over which weight cords such as the card 82a may pass and join the sash and weights. The rightward wall 83, as viewed in Figure 2, of the member 50 lies parallel with the wall of the bottom of the channel 41 of the frame member 40, and carries a pair of brackets 84 and 85 in the lower zone thereof and a similar pair, of which one, 87, is shown in Fig. 3. The several brackets are suitably secured to the wall 83 as by rivets or other means. The pairs of brackets in turn carry, preferably rotatable, horizontally extending pins 86 and 88. The pins 86 and 88 along with their supporting brackets are preferably respectively spaced appropriately away from the top and bottom ends of the member 50, whereby to distribute the forces exerted upon the member 50 substantially evenly throughout the length thereof. Two pins so spaced are adequate for small and moderate sized windows. More pins similarly carried and properly spaced may be provided in larger windows to coact with appropriate actuating means or cams, presently to be described. Preferably the pins 86 and 88 are restrained from axial movement by proximity of the ends thereof to the walls of the channel 41. Juxtaposed to the pins 86 and 88 respectively are slidable channel members 90 and 91 each containing inclined cam surfaces defined by inclined slots 92 and 93 formed in the legs of the channels respectively, which slots receive the ends of the pins 86 and 88 respectively as shown in Figures 2 and 3. The channel members 90 and 91 each have in the base thereof a longitudinally extending slot, such as 94 in the channel member 90 and 95 in the channel member 91, through which pins or bolts 96 and 97 respectively extend and guide the channels 90 and 91 in their sliding movement upwardly and downwardly within the channel 41 of the member 40 as shown in Figure 2. The bolts 96 and 97 are fixedly secured in the member 40 whereby to guide the channels 90 and 91 in their respective movements. A rack 98 is secured to the channel member 90 and an oppositely extending rack 99 is secured to the channel member 91 through which the channels are given equal and opposite upward and downward movement under the influence of the pinion 100 which engages both racks. The pinion 100 is mounted upon a pinion shaft 101; the assembly of the pinion shaft and racks being contained, journaled and supported within an appropriate housing 102, the latter being secured to the wall of the member 40 in the base of the channel 41 between the sliding channel members 90 and 91. As shown in Figure 2, the pinion shaft 101 extends through the member 40 within an appropriate bearing and sleeve and 75 out through the wall surfacing where it is en-

gaged by the lever 6. Preferably a finishing plate 103 is set into the trimming edge 43 of the member 40 whereby to protect the wall surface from movement and manipulation of the lever 6.

As viewed in Figure 3, clockwise rotation of the pinion 100 urges the rack 93 downwardly and the rack 93 upwardly thereby to draw the channel-cam bearing members 90 and 91 toward each other thereby urging the pins 86 and 88 leftwardly as viewed in Figure 3, whereby to move the box member 50 leftwardly, as also viewed in Figure 2, into engagement with or proximity to the adjacent edges of the sash 1 and 2. Opposite movement of the pinion 100 as induced through the lever 6 and pinion shaft 101 induces opposite movement of the cam channels 90 and 91 and opposite movement of the member 50. It will be appreciated that the angled slope of the slots 92 and 93 and the corresponding edges thereof which respectively bear upon the pins 86 and 88 taken with the size of the pinion 100 will give any desired mechanical advantage for moving the box member rightwardly and leftwardly as viewed in Figure 2, and the exertion of substantially any desirable force upon the edges of the sash. Similarly the manual effort required to turn the lever or crank 6 can be reduced to any reasonably desired minimum while producing the desired force and motion in the member 50.

As shown in Figures 2 and 4 I prefer that a groove 110 be provided in the side and bottom edges of the lower sash 2, and that a similar groove 112 be provided in the side and top edges of the upper sash 1. Preferably also I prefer that there be disposed in these grooves a rubber or rubber-like sealing member 111 in the groove 110 and 113 in the groove 112. Preferably each of the rubber-like sealing members or strips 111 and 113 are of substantially half round construction standing somewhat higher than the depth of the respective grooves but preferably being of cross-sectional area somewhat less than each of the respective grooves whereby to be flattened in resilient compressed contact between the bottoms of the grooves and the adjacent surfaces with which they have contact. In the same way I prefer that a groove 114 be provided in the meeting rail of the lower sash 2 and contain a rubber-like strip 115 formed similarly to the strips 111 and 113 to bear upon the juxtaposed inclined surface of the meeting rail of the upper sash. When the sash are in the closed position as shown in Figure 4, the influence of the hasp 5, urging the lower sash downwardly and the upper sash upwardly compresses the portions of the sealing members 111 and 113 adjacent the head and sill against the head and sill of the frame respectively and compresses the sealing member 115 between the base of the channel 114 and the inclined face of the meeting rail of the upper sash substantially as shown in Fig. 4. Even in the absence of the sealing members 111, 113 and 114 the influence of the hasp or other means for moving the sash respectively as above mentioned will bring tight joints between the meeting rails of the sash and the head and sill respectively, but with the provision of the yielding rubber-like sealing members lesser forces are required to bring about more satisfactory fluid-tight seals, and the rubber-like sealing members tend to compensate for irregularities in tolerances and dimensions which may well be incident to quantity production of either the sash or frame members and more particularly to the tendency of wooden sash members to warp or distort under

the influence of changing weather conditions. Apart from the influence of the hasp 5 I prefer that the sash weights be so balanced with respect to the respective sash that the upper sash will normally tend to bear with light but measurable force against the head of the frame and the lower sash will tend to overbalance its respective weights whereby to bear with moderate pressure against the sill of the frame through the respective rubber-like seals. It will be observed with particular reference to Figure 2 that when the box 50 is moved leftwardly from the position shown in Figure 2 that the sash will tend to be respectively engaged by the inclined surfaces 32 and 56 of the flanges 30 and 55 respectively on the outward side tending to move the upper sash inwardly and that the complementary inclined surfaces of the flanges 34 and 53 will tend to move the lower sash 2 outwardly; that is, upwardly as viewed in Figure 2, whereby to urge the meeting rails of the respective sash into forcible contact whereby to compress the seal 115 and/or to bring the inclined meeting surfaces into tight engagement. In Figure 2 I have shown substantial clearance between the guiding ribs 33 and 54 with the respective sash whereby to permit relative movement between sash within the channels 35, 36, 51 and 52 whereby to compress the seal 115 or to bring the meeting surfaces into contact prior to contact between the faces of the sash adjacent the ribs 33 and 54 with said ribs respectively. It will be appreciated however that the sloping or converging surfaces of the sides of the channels 35, 36, 51 and 52 may be proportioned with respect to the thickness of the sash as to grip the corner edges of the sash to make tight connections therewith with or without moving the sash bodily toward or away from each other and/or prior to or following initial contact between the seals 111 and 113 and the bottoms of the channels. One of the advantages of my invention lies in the facility with which such variants may be enjoyed in the practice of my invention.

As shown in Figure 2 the parts are in a median position. Clockwise rotation of the crank 6 moving the member 50 leftwardly will bring about tight sealing contact and engagement between the right and left edges of the sash and the channels 35, 36, 51 and 52, whereby to hold the sash securely either in the closed position shown in Figures 1 and 4, or in any other position of either or both the sash as may be desirable. In the position of the parts represented in Figure 2 either the sash 1 or 2 may be freely raised or lowered; it being one of the advantages of my invention that there is no possibility of the sash sticking or resisting raising and lowering that cannot be overcome by the ready outward movement of the member 50 through which the sash are released for free raising and lowering in about the position of the parts shown in Figure 2. In this position of the parts it will be observed that the channels 35, 36, 51 and 52, while loosely contacting or engaging the lateral edges of the sash afford ample guidance for the desired movement of the sash while offering no substantial resistance to such movement. On the other hand forcible movement of the member 50 toward the member 20 will so positively grip the sash in any desired position of either or both of them that involuntary movement thereof can be securely prevented. In this respect my window offers a substantially burglar-proof construction because even if the

sash were "jimmied" from its lower-most position still it would not then become freely movable because the resistance afforded by the grip upon the sash of the members 21 and 50 would persist even after a strained initial movement and even after the hasp 5 or any other such instrumentality were broken by a "jimmy." For like reasons children too small to reach or operate the operating handle 6 (which handle can, of course, be made removable against the contingency of undesired manipulation by larger children) will be unable to move the sash from the position that will afford desired ventilation for their sleeping quarters without offering the child either the hazard or temptation of falling through the window opening.

When the member 50 is moved rightwardly from the position shown in Figure 2, it will be seen that the sash may be readily removed from either or both their respective guiding channels for the purpose of cleaning, replacement or repair. For washing it is most convenient to lower the sash 1 down to substantially the level of the lower sash 2 and then swing the right ends of both sash, as viewed in Figure 2, inwardly, pivoting the sash loosely and separately in the channels 35 and 36 until the outside face of the upper sash is freely accessible for cleaning. Thereafter the upper sash may be allowed to rise under the influence of the weights 23 and 81 in and adjacent its guiding channels 35 and 52, whilst the outer surface of the lower sash is being cleaned. In like manner in the course of new construction the complete frames will be installed in the building walls and then left sashless until such time as the sash are desired to be installed by mere manipulation of the member 50 and the attachment of the sash to their respective sash weight cords.

The same facility of movement of the member 50 that permits the insertion and removal of the sash 1 and 2 also facilitates the insertion and removal of storm sash or screens for association with and removable attachment to the angled flanges 28 and 44 and closing contact with the head flange 12 and the sill portion 16 of my window frame, see Figs. 6 and 7. In Figure 6 the member 50 has been moved to substantially its extreme rightward position, and it may be assumed that the sash 1 and 2, suspended by their supporting cords, have been held inwardly of the window frame whereby to permit the insertion of the screen or storm sash 120 through the opening between the edge 31 of the flange 30 and the edge 57 of the flange 55. The screen or storm sash 120 may have been given an inclined upward movement under the suspended window sash 1 and 2 whilst the latter are held inwardly; it being practicable to move and insert the screen 120 so that its upper edge preferably first contacts the under surface of the head 10 of the frame inwardly of the flange 12 thereof whereby to permit the bottom edge of the sash to clear the step 17 as it is swung leftwardly as viewed in Figure 4, about its top edge as a center. After the screen 120 has been swung generally into the zone of the outside reveals behind the angled flanges 28 and 44 and outwardly of the flanges 30 and 55 it can then be freely moved rightwardly with its right frame member 121 lying more or less within and between the legs of the diaphragm 48. From this position the left frame member 122 of the screen 120 may be moved and swung to the right of the edge 29 of the flange 28 to permit the brackets 75 and 93 to engage the outer face of the bead 29 whilst the shoulder 124 of the frame member 123 engages the inner face of the bead 29. On the rightward frame member or edge 121 of the sash 120 I provide movable U-shaped clips 125 which may be rotated about the axis 125a from the position shown in Figures 6 and 7 to a position where the outer leg 126 of the clip 125 freely exposes the shouldered face 127 of the frame member 121 to contact with the inward face of the bead 45 of the angled flange 44. With the clips 125 in their open position the screen 120 may be swung to the position shown in Figure 6 and then a quarter turn of the clips 125 will bring the legs 126 thereof into the position shown in Figure 6 to secure the screen in place. Meanwhile the bottom edge 130 of the sash 120 may rest upon the sill portion 16 as shown in Figure 7, and the top edge 131 may be spaced downwardly somewhat from the under surface of the head 10 but will have contact with the inward face of the flange 12, the rightward face as viewed in Figure 7, which lies in the plane of the outward face of the sash 120 as well as in the plane of the outward faces of the angled flanges 28 and 44, see Fig. 4. After the screen or storm sash 120 is in place the sash 1 and 2 may be returned to operative relation to the channels 35, 36, 51 and 52 where they may again be guided and/or grasped by leftward movement of the member 50 and used without interference from the screen or storm sash 120 whilst the latter remains in the position shown in Figures 6 and 7. Removal of the screen or storm sash 120 will require merely the reversal of the operations mentioned for insertion, all of which is preferably done from the interior of the room or building in which my window is disposed.

When the movable element 50 is in about the position shown in Figure 6, i. e., in a position of extreme rightward movement into the channel 41, the pins 86 and 88 will have been moved to the outward ends of the inclined slots 93 and 92 as shown in dotted lines at 86a and 88a respectively. It will be observed that the slots terminate adjacent straight vertical edges 92a and 93a on the legs of the channels 90 and 91. Further movement of the channels 90 and 91 toward each other as induced by the racks and pinion will move the channels relative to the pins 86 and 88 whereby to position the pins on the surfaces 92a and 93a beyond the open ends of the slots 92 and 93 and thereby free the pins 86 and 88 from retained engagement with the channels 90 and 91. In this "free" position the member 50 along with the pins 86 and 88 and their supporting brackets may be bodily withdrawn from the channel 41, flexing the diaphragm 48 in the course of such movement. When the member 50 is withdrawn from the channel 41 it may be swung leftwardly and upwardly as viewed in Figure 2, the diaphragm 48 serving as a strap hinge to facilitate such movement whereby to open the channel 41 for inspection and/or repair of the channel, rack and pinion mechanism or replacement of the parts thereof. Conversely in the initial assembly of the parts the order of operations may be reversed; the rack, pinion and channel mechanisms being first inserted and mounted in the channel 41 and then the channels 90 and 91 drawn together in their most proximate positions for receipt of the pins 86 and 88 upon the surfaces 92a and 93a. Thereafter movement of the channels

90 and 91 to positions similar to that shown in Figure 3, draws the member 50 inwardly of the channel 41 more or less as may be desired.

In the initial assembly of the whole frame, the head, sills and head members are first secured together then the member 50 is fitted carefully, preferably by grinding its ends to have a smooth sliding fit with the head and sill in the intended path of its operative movement. Thereafter the member 50 is preferably secured to the diaphragm 48 as above mentioned and may thereafter be bodily inserted into and removed from the channel 41 while retaining its bond with the diaphragm 48 as above described.

As shown in Figure 2 the end of the pinion operating shaft 101 preferably has a square or non-circular shank upon which the hub of the lever 6 may be removably attached. As above mentioned removability of the lever 6 permits the sash 1 and 2 to be gripped in any desired position and left in such position substantially tamper-proof by removal of the lever 6. The removability of the lever 6 also plays another role. When the sash are firmly gripped between the members 50 and 21 the lever 6 may be removed and reset on the non-circular shank of the shaft 101 to be proximate to the removable stop pin 6a but spaced therefrom in the direction which will permit substantially one full turn of the lever 6 in the direction to release the sash before contacting the stop pin 6a. I prefer that the inclination of the cam slots 82 and 93 taken with the geared relation of the pinion 100 to the racks 88 and 99 be such that a little less than one full turn of the lever 6 will move the member 50 just enough to permit substantially free movement of the sash 1 and 2 for any desired upward or downward adjustment thereof. The removable stop pin 6a therefore reminds the manipulator to turn the pinion 100 no more than necessary for this simple and ordinary regulation of the position of the sash. When greater movement of the member 50 is desired the stop pin 6a is merely removed from the plate 103 so that the lever 6 may be turned as many revolutions as desired for any of the purposes above described. It may be mentioned in passing that movement of the member 50 away from the member 21 will so thoroughly free the sash of any material frictional engagement in the sash guiding channels of these members that spring sash balancers may be advantageously employed in lieu of the conventional sash weights since the bane of employment of sash balancers has been the unpredictability of the degree of frictional drag existing between sash and window frames.

Preferably the overall dimensions of the exterior of the frame of my window may be proportioned to correspond with even multiples of the height and length of face brick with appropriate mortar joints. Aided by such proportion my window frame and particularly the reinforced head 10 with its lateral extensions 10a, see Fig. 1, is especially adapted to be incorporated in brick and masonry walls as substantially integral load bearing part thereof and is peculiarly adapted to being so integrated into the wall structure as to have a weather tight bond therewith. Preferably the whole window is mounted in the wall structure as the same is being constructed; the sill 15 resting upon and being set on a grout or mastic cushion 149, see Fig. 4, while the latter is in a plastic state and receptive to receive the sill in a weather tight bond. Thereafter the brick and masonry walls are prefer-

ably built up around the side frame members with mortar or mastic poured or troweled between the abutting masonry units and the adjacent faces of the side frame members. Preferably the masonry is carried up to and laid under the lower surfaces of the head extensions 10a whereby to support these extensions in load bearing relation so that the load of the masonry above the head is carried to the masonry walls through the extensions 10a as well as through the side frame members and the sill. As shown especially in Figure 4, the head has both upwardly and downwardly extending flanges 11, 12 and 13. While the flanges 12 and 13 are preferably of size and proportion to be pleasing to the eye the flange 11 which is bonded into the masonry construction may be of whatever size is necessary to strengthen the head to serve not only as the head of the frame but also as the load bearing lintel. As suggested in Figure 4 the flange 11 may have an enlarged bead substantially in the form of an I-beam for desirable reinforcement. By thus incorporating the functions of head frame and lintel into the same member I avoid the air and moisture leakage which inevitably tends to enter between the lintel and the head of the window frame where these elements are separate members. By disposing the flanges 11 adjacent to and behind the brick or other outer wall surface I interpose a barrier to the seepage of air and moisture through the mortar joints between the brick and the head and the back-up masonry. The wall structure in its bond to and contact with the flange 11 also stiffens and strengthens the flange whereby to afford a mutually self-sustaining structure.

Although I have illustrated a preferred embodiment of my invention in which wooden sash have been illustrated it will be apparent that metal sash or rubber or plastic trimmed sash will have equal if not greater utility within the precepts of my invention and because of the relative thinness of the latter will require commensurately reduced guiding channels and will permit similar reduction in the size of the related parts.

While I have illustrated and described my invention in terms of a window in which the sash movement is vertical, I also contemplate that the window may be usefully installed when turned at 90°, as with the sash in vertical planes but moving horizontally, from the position referred to in the foregoing description whereby to eliminate the need for the balancing effect of the sash weights but otherwise retaining and embodying the other advantages and effects of my invention.

Other changes, modifications and improvement in and upon my invention will suggest themselves to those skilled in the art who come to understand or practice the teachings and precepts thereof, and I do not care to be limited to the preferred and exemplary form or forms of my invention herein specifically illustrated and described nor in any manner other than by the claims appended hereto.

I claim:

1. A window frame for movable sash comprising a head, a sill, a side member having a channelled cross-section and joining said head and sill, a movable sash engaging element having sliding contact at its ends with said head and sill and slidably mounted in the channelled section of said side member whereby to be telescopically movable therein, pins carried by said element transversely thereof at points spaced from the ends of said element and from each other, oppositely acting op-

posed cam means movably carried by said member in the channelled section thereof engaging said pins by the relative movement of which said element is movable relative to said member and maintained in bodily alignment therewith, oppositely movable racks connected to said means, a rotatable pinion engaging said racks, and manually operable means extending in part without said member for rotating said pinion.

2. A window frame for movable sash comprising a head, a sill, a side member having a channelled cross-section and joining said head and sill, a movable sash engaging element having sliding contact at its ends with said head and sill and slidably mounted in the channelled section of said side member whereby to be telescopically movable therein, pins carried by said element transversely thereof at points spaced from the ends of said element and from each other, oppositely acting opposed cam means movably carried by said member in the channelled section thereof engaging said pins by the relative movement of which said element is movable relative to said member and maintained in bodily alignment therewith, and means for moving said cam means.

3. The combination of claim 2 in which said cam means has transversely spaced longitudinally inclined parts engaging said pins at transversely spaced points.

4. In a window frame for movable sash, end members, a fixed side member joining said end members and lying in the direction of sash movement and spaced from the edge of the sash, a side member longitudinally coextensive of said fixed member and movable transversely of the direction of sash movement and engageable with the edge of the sash and interposed between the sash and said fixed member, said fixed and movable members having spaced parallel flanges lying parallel to the plane of the window sash, means for moving said second member and selectively positioning the same relative to said fixed member, and sealing means comprising a yielding fluid impervious diaphragm extending in a direction parallel to said side members and having fluid-tight engagement therewith throughout the length thereof, said diaphragm being U-shaped in transverse section and being disposed between the flanges of said fixed and movable members.

5. In a window frame for movable sash, end members, a fixed side member joining said end members and lying in the direction of sash movement and spaced from the edge of the sash, a side member longitudinally coextensive of said fixed member and movable transversely of the direction of sash movement and engageable with the edge of the sash and interposed between the sash and said fixed member, means for moving said second member and selectively positioning the same relative to said fixed member, and sealing means comprising a yielding fluid impervious diaphragm extending in a direction parallel to said side members and having constant fluid-tight engagement therewith throughout the length thereof, said diaphragm being U-shaped in section transverse the direction of movement of said movable member and being attached to said side members respectively at the free ends of the legs of the U.

6. A window frame for movable sash comprising head, sill and side members fixedly secured together, a movable sash-engaging side element movable transversely of and coacting with one of said side members and extending substantially coextensively thereof longitudinally, and means for moving said element whereby to change the

width of the variable opening between said element and the other of said side members within which variable opening the window sash are releasably engaged, said side members having outwardly disposed angled flanges located in the reveal of the frame and having parts lying parallel to the plane of sash movement accommodating instrumentalities such as screens or storm sash introduced through the variable opening for mounting in operable association with the fixed opening defined by said flanges, said movable element having a part lying parallel to and spaced inwardly of the part of the flange of the side member adjacent thereto, the part of said movable element having an edge parallel with the edge of said part of said flange and movable in a plane parallel with said part of said flange, and a flexible U-shaped diaphragm extending the height of said parts and disposed therebetween and having longitudinal edges secured to the said edges of said parts.

7. A window frame having sash guiding parts, means for moving said parts toward and away from each other to grip and release the sash, a member spaced from and parallel to one of said parts between which and said member relative movement takes place when said parts move with respect to each other, and fluid-impervious flexible means having fluid tight engagement with said member and said one of said parts and maintaining a weather seal therebetween regardless of movement therebetween, said sealing means being U-shaped in section transverse to the plane of relative movement between said part and said member and extending in a direction transverse to the direction of such movement and being attached to said part and to said member respectively at opposite free ends of the legs of the U.

8. A window frame having sash guiding parts movable toward and away from each other to grip and release the sash, a member spaced from and parallel to one of said parts between which and said member relative movement takes place when said parts move with respect to each other, fluid impervious flexible means having fluid-tight engagement with said member and said one of said parts and maintaining a weather seal therebetween regardless of movement therebetween, said sealing means being U-shaped in section transverse to the plane of relative movement between said one part and said member and extending in a direction transverse to the direction of such movement and being attached to said part and to said member respectively at opposite free ends of the legs of the U; and means for moving said sash guiding parts toward and away from each other while maintaining said one of said parts in bodily alignment with said member comprising pins carried by said one of said parts transversely thereof at points spaced from the ends of said one part and from each other, oppositely acting opposed cam means movably carried by said member and having equally inclined surfaces slidably engaging said pins by relative movement of which said one part is movable relative to said member and maintained in bodily alignment therewith, and means for moving said cam means.

9. In a window frame for movable sash, end members, a fixed side member joining said end members and lying in the direction of sash movement and spaced from the edge of the sash, a side member longitudinally coextensive of said fixed member and movable transversely of the

direction of sash movement in engagement with the edge of the sash and interposed between the sash and said fixed member, sealing means comprising a yielding fluid impervious diaphragm extending in a direction parallel to said members and having fluid-tight engagement therewith throughout the length thereof, means for moving said second member relative to and in bodily alignment with said fixed member comprising pins carried by said second member transversely thereof at points spaced from the ends of said second member and from each other, oppositely acting opposed cam means movably carried by said fixed member and having surfaces equally inclined longitudinally of said fixed member engaging said pins by the relative movement of which said second member is movable relative to said fixed member and maintained

5

in bodily alignment therewith, and means for moving said cam means.
